LAUNDERING COMPOSITION AND PROCESS

Ralph E. Hall, Mount Lebanon, Pa., assignor to
Hall Laboratories, Inc., Pittsburgh, Pa., a cor-
poration of Pennsylvania

No Drawing. Application June 19, 1936,
Serial No. 86,157

9 Claims. (Cl. 87—5)

This invention relates to laundering, and more particularly to preventing the deposition of metals such as iron, aluminum or copper in the goods during the laundering operation. It relates 5 more especially to the prevention of yellowing of the goods by iron compounds. The present invention has been developed especially in connection with the use of alkali-metal metaphosphates in laundering in order to overcome any tendency 10 to yellowing of the goods if the metaphosphate is contaminated with iron. It is applicable, however, irrespective of the source of contamination, that is, whether the contaminating iron, aluminum or copper is derived from the metaphosphate itself or from other sources such as 15 the water employed in washing or because it is present in the goods themselves.

This application is a continuation-in-part of my copending application Serial No. 685,748, 20 filed August 18, 1933.

In my Reissue Patent No. 19,719, reissued October 8, 1935, I have described, among other things, a process of laundering goods using an alkali-metal metaphosphate, preferably sodium hexametaphosphate. Usually, a small amount 25 of soda ash or bicarbonate of soda and soda ash, or other alkali, is added to the sodium hexametaphosphate in order to overcome its slight acidity.

In carrying out the preferred washing process described in my patent, the goods are put into 30 the laundry wheel and subjected to what is known as the "break". The break consists in preliminary subjecting the goods to lukewarm water containing sodium hexametaphosphate and perhaps a small amount of soap or an additional amount of alkali. The object of the break 35 is to loosen and remove some of the dirt before the goods are subjected to the washing operation.

After the break, the water is drained off and 40 hot water is run into the laundry wheel, together with soap and some sodium hexametaphosphate and also at times additional alkali, and the goods are given the washing treatment. After the washing is completed, the wash water 45 is drained off and the goods are rinsed, preferably with rinse water containing a small amount of sodium hexametaphosphate.

Unless great care is taken in its preparation, 50 sodium hexametaphosphate is likely to be contaminated with a few hundredths of 1% of the iron compounds, probably iron phosphate. In the alkaline solutions employed in the break and washing operations, this iron may be converted 55 into ferric hydroxide which is deposited in the goods, resulting in imparting a yellowish tinge to white goods. In neutral or but slightly alkaline solutions, the iron is held in solution by the hexametaphosphate which forms a soluble iron 60 complex with it, but in the strongly alkaline so-

lutions employed for washing, the alkalinity causes the conversion of the iron into the ferric hydroxide which is insoluble and is entrained in the fabrics, causing the familiar yellowing of the fabrics.

Iron may also be introduced into the washing operations from other sources such as iron in the water supply or iron may be carried in the goods themselves. Soluble iron salts from any source, when they encounter the high alkalinity 10 of the wash water, are converted into the insoluble iron hydroxide which yellows the goods.

Aluminum and copper salts or soaps, if present, are deposited in the goods from the highly alkaline solutions employed in washing. Aluminum 15 may be present in the water where alum or sodium aluminate is used in treating the water prior to the washing operation. Small amounts of aluminum may also be dissolved by the water where aluminum apparatus is employed. Aluminum may also be carried into the wash water on the goods themselves. Aluminum, if present, may form insoluble aluminum soaps by reaction with the usual soaps employed in 20 washing in the presence of the highly alkaline 25 solution. These aluminum salts or soaps form an objectionable deposit in the goods, entrapping soil and preventing thorough cleansing of the goods.

The water may be contaminated with small 30 amounts of copper due either to the corrosion of brass pipe or to the dissolving action of the highly alkaline wash water on copper apparatus where such metal is employed. The copper may be precipitated in the highly alkaline wash water as colored deposits of hydroxide, silicate or basic carbonate, depending upon the particular alkali used in the laundering operation, these colored deposits being entrained in the goods.

Although sodium hexametaphosphate will sequester iron, aluminum and copper in soluble metaphosphate complexes, in neutral or only slightly alkaline solutions these metals are precipitated in highly alkaline solutions. I have found, however, that these metals may be kept 45 in solution in inert colorless form in the alkaline solutions encountered in laundering operations, by the use of tartrates, oxalates or citrates which will combine with the metals to keep them in a soluble colorless condition. Referring to the tartrates by way of example, I may employ the alkali-metal tartrates, ammonium tartrates, or tartaric acid, which may be considered as hydrogen tartrate and which when added to the alkaline solution forms the tartrate. I have 55 found that the compounds having the formula $R_2C_4H_6O_6$, in which each R stands for a member of the group consisting of hydrogen, ammonium and an alkali-metal, are suitable for this purpose. Any of these tartrates may be used, such for ex- 60

ample as cream of tartar. I may use sodium tartrate, potassium tartrate, or the sodium-potassium tartrate, or the acid tartrates, or even tartaric acid, so long as the compound yields the tartaric-acid radical in soluble form and does not itself introduce discoloring matter.

Likewise, the oxalates or citrates of the alkali-metals or ammonium; or oxalic acid or citric acid may be used in place of the tartrates or tartaric acid to prevent the deposition of iron, aluminum or copper in the goods in alkaline solution.

For the purpose of preventing the deposition of iron, aluminum or copper in alkaline solutions, I use in conjunction with an alkali-metal hexametaphosphate, a compound having the formula R_xM in which each R stands for a member of the group consisting of hydrogen, ammonium and an alkali-metal, and in which the acid radical M is selected from the group of acids consisting of tartaric acid, oxalic acid or citric acid, and in which x is the valence of the radical M.

If the alkali-metal hexametaphosphate, such as sodium hexametaphosphate, employed is contaminated with a small amount of iron or other contaminating metal, enough of the tartrate, oxalate or citrate is mixed with the metaphosphate to sequester the iron or other contaminating metal into the tartrate, oxalate or citrate molecule where it is kept in a soluble colorless form so that it is not deposited upon the goods. For sodium hexametaphosphate contaminated with, say, about $\frac{1}{100}$ of 1% of iron, I may use an amount of tartrate which corresponds to 5% by weight of the metaphosphate used. This amount will vary naturally with the amount of iron present in the metaphosphate or derived from the water or goods and will also vary according to the particular contaminating metal which it is desired to sequester and according to the particular agent used for this purpose.

By the use of the tartrates, oxalates or citrates, alkali-metal hexametaphosphates may be used which are not entirely freed from iron compounds or compounds of other contaminating metals in their manufacture. The term "alkali-metal hexametaphosphate" includes not only sodium hexametaphosphate, but the hexametaphosphates of the other alkali-metals, such as potassium, ammonium, lithium, etc.

In general, the use of the tartrates, oxalates or citrates is applicable to various cleansing operations to which the goods are subjected in laundering, such as the "break", the "suds", and even the rinse.

While I have specifically described the preferred procedure in carrying out my invention, it is to be understood that the invention is not so limited, but may be otherwise embodied and practiced within the scope of the following claims.

I claim:

1. A process of laundering goods in the presence of iron, aluminum or copper, which comprises immersing the goods in an alkaline solution containing an alkali-metal hexametaphosphate together with a water-soluble compound containing an acid radical of the group consisting of tartaric acid, oxalic acid and citric acid, which prevents deposition of the metals in the goods by the alkaline water.

2. A process of laundering goods in the pres-

ence of iron, aluminum or copper, which comprises immersing the goods in an alkaline solution containing an alkali-metal hexametaphosphate together with a water-soluble compound having the formula R_xM in which each R stands for a member of the group consisting of hydrogen, ammonium and an alkali-metal, and in which the acid radical M is selected from the group of acids consisting of tartaric acid, oxalic acid and citric acid, and in which x is the valence of the radical M.

3. A process of laundering goods in the presence of iron, aluminum or copper, which comprises immersing the goods in an alkaline solution containing an alkali-metal hexametaphosphate together with a water-soluble compound containing the tartaric acid radical, which prevents deposition of the metals in the goods by the alkaline water.

4. A process of laundering goods in the presence of iron, aluminum or copper, which comprises immersing the goods in an alkaline solution containing an alkali-metal hexametaphosphate, and preventing the deposition of the metals in the goods by incorporating in the alkaline solution a compound having the formula $R_2C_4H_4O_6$, in which each R stands for a member of the group consisting of hydrogen, ammonium and an alkali-metal.

5. A process of laundering goods in the presence of iron, aluminum or copper, which comprises immersing the goods in an alkaline solution containing soap and an alkali-metal hexametaphosphate, and preventing the deposition of the metals in the goods by incorporating in the alkaline solution a compound having the formula $R_2C_4H_4O_6$, in which each R stands for a member of the group consisting of hydrogen, ammonium and an alkali-metal.

6. As a washing composition, a mixture of an alkali-metal hexametaphosphate and a compound having the formula $R_2C_4H_4O_6$, in which each R stands for a member of the group consisting of hydrogen, ammonium and an alkali-metal, which compound prevents deposition of iron, aluminum and copper in the goods by alkaline water.

7. As a washing composition, a mixture of an alkali-metal hexametaphosphate and a water-soluble compound containing the tartaric acid radical, which compound prevents the deposition of iron, aluminum and copper in the goods by alkaline water.

8. A washing composition containing an alkali-metal hexametaphosphate and a water-soluble compound containing an acid radical of the group consisting of tartaric acid, oxalic acid and citric acid, which prevents deposition of iron, aluminum and copper when the composition is added to alkaline water.

9. A washing composition containing an alkali-metal hexametaphosphate and a water-soluble compound having the formula R_xM , in which each R stands for a member of the group consisting of hydrogen, ammonium and an alkali-metal, and in which the acid radical M is selected from the group of acids consisting of tartaric acid, oxalic acid and citric acid, and in which x is the valence of the radical M.
